UNITED STATES PATENT OFFICE.

HERBERT C. WILLIAMSON, OF CHICAGO, ILLINOIS.

GRENADE.

1,231,228.

Specification of Letters Patent. Patented June 26, 1917.

Application filed March 2, 1916. Serial No. 81,591.

To all whom it may concern:

Be it known that I, HERBERT C. WILLIAMSON, a citizen of the United States, residing at Chicago, in the county of Cook and State 5 of Illinois, have invented certain new and useful Improvements in Grenades, of which the following is a specification.

Hand grenades as usually manufactured are more or less complicated affairs which 10 must be specially constructed and loaded in a special manner, all of which tends to increase the cost of the same, as well as to make them more difficult to use. The present invention relates to grenades which are 15 adapted to be thrown by hand or by means of suitable throwing apparatus. Among the objects of this invention are to provide an exceedingly simple and efficient grenade which may be cheaply constructed, and 20 which will be efficient in use; to provide a grenade in which an ordinary shell such as a shot gun shell may be used for exploding the same; and in general, to provide such an improved device or construction as will 25 be more fully described hereinafter.

In the accompanying drawings illustrating this invention:

Figure 1 is a side elevation;

Fig. 2 is a longitudinal sectional view; and 30 Fig. 3 is a cross sectional view.

The use of explosive shells such as commonly employed for shot guns is well understood, and in accordance with my invention, I utilize such shells for the explosive member, these shells being preferably charged with a charge of explosive material larger and stronger than ordinarily employed in shot guns. In order to utilize these shells, I provide a grenade comprising 40 a body portion 4, which is preferably made of cast metal, such as cast iron, and is somewhat heavier at one end than at the other. This body portion is made of convenient size for handling, and when used as a hand grenade, will preferably be made substantially egg shaped, as shown. This body portion or container is preferably provided with ribs or projections 5, which may be arranged in any desired manner, but are preferably 45 longitudinal and extend throughout the greater length of the container. These ribs serve to make more effective fragments for causing injury, and may be proportioned so as to cause the body to break into more or 50 less portions and in different ways, as may be desired. The body or container is pro-

vided with a central longitudinal bore 6, of the proper size to receive an ordinary shell 7, such as commonly used in shot guns or the like. A plurality of radial grooves 8 may 60 be arranged along the central bore 6, so as to assist in the rupturing action of the charge. These grooves preferably increase in depth from the smaller end toward the larger end, so as to make the breaking resistance about equal throughout the body. The body is provided with a threaded recess or aperture 9, in alignment with the central bore, this recess terminating in a shoulder 10, which serves as an abutment for the 70 flange 11 of the cartridge shell. A threaded block or plug 12 screws into the recess 9, and its inner end engages closely with the end of the cartridge shell. This block is provided with a firing pin 13, which is 75 adapted to move longitudinally in the central hole 14 provided for the same. The pin 13 has a recess 15 in one side thereof, which is engaged by the inner end of a set screw 16, which serves to prevent the pin from becoming 80 disengaged from the block, although allowing the necessary longitudinal movement. A disk or plate 17 is secured to the firing pin 13 in any suitable manner, as by means of a nut 18. This plate is preferably 85 of convex or segmental form, so as to correspond with the outline of the large end of the body 4.

When my improved grenade is to be used, a loaded cartridge shell 7 is inserted in the 90 central bore of the grenade, and the plug or block 12 is screwed into position, and engages with the flange 11, thereby holding the shell firmly in position. The shell or cartridge is provided with the usual detonating cap 19, which is adapted to be engaged by the projection 20 on the end of the firing pin 13, but this projection is normally out of engagement therewith. The disk or plate 17 is then secured in position 95 and the device is ready to be used. If it is thrown or dropped, the heavy end will strike first, and as soon as the plate 17 comes in contact with the earth or any resisting object, it forces the pin 13 inwardly, thereby 100 causing the projection 20 to strike the cap 19 and explode the charge in the shell, which will cause the fragments to be thrown in all directions. The plate 17 is made in this peculiar form so that even if the grenade 110 strikes at an acute angle, or in fact strikes in any way so that the plate comes in con-

tact with a non-yielding object, the pin will be forced inwardly, thereby insuring the exploding of the device. It will be seen from the relative proportions of the parts of this 5 grenade that, even if the body portion should strike in advance of the firing pin, the weight of the pin and attached parts would be sufficient to cause the explosion of the charge.

10 By means of this arrangement, it will be seen that I have provided a grenade which may be used in connection with ordinary paper shells or other cartridges such as those used for ordinary shot guns, and which 15 will be exceedingly effective in use. It will be observed that my improved grenade may be varied in shape and size without departing from the principal features of the invention, and therefore I do not wish to limit 20 myself to the exact arrangement or construction herein shown and described, except as specified in the following claims, in which I claim:

1. In a hand grenade, the combination of 25 a body comprising a cylinder closed at one end and having a threaded open end, the inner wall of the cylinder being provided with one or more transverse grooves, the outer wall of the cylinder being provided 30 with a plurality of longitudinal ribs which taper outwardly from the closed end toward the open end, a shell fitting in said cylinder, a threaded plug in the open end for engagement with said shell, a firing pin mounted 35 in said plug, and a cup-shaped disk secured to said pin and embracing the adjacent end of the body portion, said pin and disk being of sufficient weight so that when the grenade 40 is thrown, the cartridge will be exploded, even if the body portion strikes in advance of the disk.

2. In a grenade, the combination of a body portion having a central bore for re-

ceiving a cartridge, a threaded recess in the end of the body portion having a shoulder 45 at the bottom thereof to receive the cartridge rim, a hollow, threaded plug fitting in said recess, the inner end of the plug being closed but having a small central hole, a firing pin fitting in said hollow plug, said 50 pin having a small projection adapted to pass through said central hole for engagement with the cap of the cartridge.

3. In a device of the character set forth, the combination of a body portion having 55 exterior projections and heavier at one end than the other, a longitudinal bore extending in from the heavier end, annular grooves along said bore, a threaded recess in said heavier end having a shoulder in the bottom 60 thereof, a cartridge fitting in said central bore, with its flange resting against said shoulder, a threaded plug for said recess, adapted to engage with the end of the cartridge, a firing pin slidably mounted in said 65 plug, and a disk secured to said firing pin.

4. In a device of the character set forth, the combination of a body portion which is heavier at one end than the other, longitudinal ribs formed integrally with said body 70 portion, a bore extending inwardly from the heavier end, a threaded recess concentric with said bore, a cartridge fitting in said central bore and having a flange engaging 75 with the bottom of the recess, a threaded plug engaging with said recess and adapted to hold the cartridge in position, a firing pin in said plug adapted to move longitudinally therein, said pin having a projection for engagement with the cartridge cap, and 80 a disk secured to said pin, the arrangement being such that the disk will tend to move the pin inwardly upon engagement with some non-yielding object.

HERBERT C. WILLIAMSON.
